Primary Examiner — Elizabeth J Oswecki(74) *Attorney, Agent, or Firm* — Fraser Clemens Martin & Miller LLC; Jacob M. Ward(57) **CLAIM**

The ornamental design for a face shield, as shown and described.

DESCRIPTION

FIG. 1 is a top perspective view of a face shield, shown in an unclasped position showing my new design;

FIG. 2 is a top perspective view of the face shield of FIG. 1, shown in a clasped position with a removable shield shown in broken lines;

FIG. 3 is a bottom perspective view of the face shield shown in FIG. 1, shown in an unclasped position;

FIG. 4 is a bottom perspective view of the face shield shown in FIG. 2, shown in a clasped position;

FIG. 5 is a top plan view of the face shield shown in FIG. 1, shown in an unclasped position;

FIG. 6 is a bottom plan view thereof;

FIG. 7 is a front elevational view thereof;

FIG. 8 is a rear elevational view thereof;

FIG. 9 is a left side elevational view of thereof; and,

FIG. 10 is a right side elevational view thereof.

In the drawings, the broken lines in FIGS. 1–10 depict portions of the design that form no part of the claim.
